OUTRIGGER SUPPORT FOR MOBILE CRANE
OR SHOVELMartin C. Boysen, Joseph, and Kenneth E. Towers,
Enterprise, Oreg.

Application April 12, 1954, Serial No. 422,442

5 Claims. (Cl. 212—145)

This invention is a powered outrigger support for mobile cranes or shovels and a mobile crane or shovel having supports of this kind.

One object of the invention lies in the provision of a mobile crane or shovel having mechanically movable outrigger supports operable in accordance with manual selection.

Another object of the invention lies in the provision of an outrigger support for a mobile crane or shovel and having a support jack carried by an extensible beam and movable into and out of supporting position according to manual selection.

Another object of this invention lies in the provision of an outrigger support for a mobile crane or shovel having a single power unit adapted to extend an extensible beam and shift a supporting jack to its supporting position at manually selected predetermined extended positions of said beam. These and other objects of the invention will become apparent during the course of the following description and the accompanying drawings wherein a preferred form of the invention is shown. It should be understood however that the drawings and description are illustrative only and are not intended to limit the invention except insofar as it is limited by the claims. It should also be understood that we use the term "mobile crane or shovel" generically whether the unit is being employed in the work as a shovel, drag line, hoe, crane, clam shell, or other analogous function.

In the drawing:

Figure 1 is a fragmentary rear elevation of a mobile crane employing the improved outrigger support.

Figure 2 is a vertical longitudinal fragmentary cross sectional view upon an enlarged scale of the end portion of one outrigger;

Figure 3 is a vertical transverse cross section taken at line 3—3 of Figure 2 and upon a further enlarged scale;

Figure 4 is a view similar to that of Figure 2 showing a modified outrigger which is adapted for greater extensions;

Figure 5 is a horizontal cross section of the device shown in Figure 4; and,

Figure 6 is a transverse cross section at line 6—6 of Figure 5.

Referring now more particularly to the drawing, in Figure 1 we have disclosed a mobile crane or shovel indicated in general by the numeral 10 as comprising a carrier frame 11 supported on wheels of which the rear driving wheels 12 are disclosed. The frame is provided with the conventional mounting plate 13 upon which is secured the ring gear 14 forming the base upon which the turn table 15 is rotatably supported and by means of which it is driven. Conventionally, the turn table 15 supports a cab and winch mechanisms and a vertically tiltable boom operably united with the winch mechanism by means of cables, but since this structure is well known in the art and forms no part of the present invention, it has not been shown in the accompanying drawings.

2

To obtain maximum lifting capacities of mobile cranes or shovels and to relieve operating stresses and strains upon the mobilizing carrier, it is necessary that outriggers be employed to provide a solid base of operation. As is conventional, there are two sets of outriggers used. One set is located amidship just behind the carrier cab (not shown) and one set across the rear of the carrier frame. Inspection of Figure 1 will reveal that the last-mentioned set is disclosed for the purpose of the present work.

It is necessary that outriggers be extendible and even though not always necessary, for sake of convenience, the outriggers consist of a divided box-like structure containing two sliding beams, one of which may be slid out on each side to extend the effective width of the outrigger and thus the operating base beyond the overall width of the supporting wheels 12.

In the present disclosure we provide a pair of juxtaposed outrigger boxes 16 each one of which telescopically contains a tubular outrigger beam 17. As here shown, the boxes 16 are substantially square in transverse cross section (see Figure 3) however, it will be understood that any desired cross sectional shape may be employed with only the one restriction that the outrigger boxes and beams be non-rotatable with respect to each other and the frame. The outrigger beams 17 are longitudinally reciprocable within the boxes 16 and are provided at their outer ends with supporting jacks 18 which are normally disposed in the inoperative position within the beams 17 axially thereof. At their outer ends the jacks 18 are provided with bases or floats 19 which constitute supporting feet for the outriggers. Each float 19 is carried on the end of a square thread jack screw 20 which cooperates with the tubular leg 21 of the jack 18 to allow for varying the length of individual jacks 18 as required by variations in the surface 22 from which the crane or shovel is to be supported.

At its inner or upper end, each jack 18 is provided with a transversely extending pin 23 which may or may not have rollers 24 as desired, and the ends of the pin 23 or the rollers 24 are adapted to traverse the length of a cam 25 comprising a pair of spaced bars 26—26 welded or otherwise secured on the inside faces of the side walls forming a part of the outrigger beams 17. At the inner ends, the cam bars 26 have recessed or sunken lips 27 and at the outer ends they are turned upwardly to form stops 28.

The jack leg 21 is provided at its lower or outer end with a pair of spaced ears 29 which receive and pivotally secure a brace bar 30 having its opposed end pivotally secured at 31 within the outrigger beam 17. Inspection of the dotted line position of Figure 2 and the full line positions of Figure 1 will reveal the function of this brace bar 30 as being to brace the jack 18 against lateral strains and also to insure its proper movement while being extended or retracted from the beams 17.

A conventional hydraulic cylinder 32 is anchored at 32' to a point fixed relative to the frame 11 and has its piston rod 33 pivotally secured to the inner end of the jack leg 21 preferably at the axis of the pin 23. When manually controlled hydraulic fluid causes the cylinder 32 to press outwardly, the piston rod 33 exerts longitudinal pressure on the jack 18 and since prior to entrance into an aperture 35 the latch 34 is disposed to prevent movement of the inner end of the jack leg 21 upwardly along the cam bars 26 from the recessed lip 27 the pressure applied causes the beam 17 to be telescopically extended outwardly from the outrigger box 16.

Inspection of Figure 2 will reveal that the outrigger box is provided with a plurality of apertures 35 selected ones of which are stopped by means of plugs 36, the plugs being movable from one aperture 35 to another

as selected. Obviously, the pressure applied to the jack 18 by the piston rod 33 urges the inner end of the jack leg 21 to traverse the cam 25 but the latch or dog 34 prevents its movement until such time as the dog 34 is permitted entrance into an aperture 35 and assumes the position indicated by dotted lines of Figure 2 by means of the pressure exerted thereupon by the inner end of the jack 18 being urged upwardly by the lips 27 of cam 25, whereupon the jack is extended to the dotted line position by continued pressure of motor 32. Movement of the outrigger beam 17 is precluded by reason of the dog 34 having gained entrance to the aperture 35 thus insuring accurate positioning and movement of the jack 18. It will also be noted that while the jack 18 is in its supporting position, the piston rod 33 is in a position supporting the latch or dog 34 and precluding its return pivotal movement a distance sufficient to be withdrawn from the aperture 35 and therefore when the pressure of cylinder 32 is reversed to withdraw the jack 18 from its supporting position, inward movement of the beam 17 is precluded by the latch 34 until such time as the jack 18 has again assumed its normal position shown in full line of Figure 2 whereupon the latch 34 is permitted to return to its full line position and the beam 17 is drawn inwardly into the outrigger box 16. As indicated in the drawing, the jack 18 is provided with a laterally extending pressure plate 37 providing a relatively large supporting surface for the upper end of the jack 18.

In the device disclosed in Figures 1, 2, and 3, of the drawing, we disclose the pivoted dog type latch 34 wherein extension of the beam 17 is limited to the overall length of the jack 18, since it is necessary that the latch remain within the outrigger box at all times. However, in Figures 4 through 6 we have shown a modified latch 34' which permits extension of the outrigger beam to any extent limited only by the length of the outrigger box and latch mechanism. In this device the jack and power mechanisms are identical but the latch 34' is formed with a confining lip 40 which confines the inner end of the jack 18 and precludes its movement over the cam 25 and has an inwardly extending arm 41 provided with a right angle hook or finger 42 which extends through an aperture 43 in the outrigger beam 17 and bears against the inner side face of the outrigger box 16. Spaced along the side wall of the outrigger box 16 are a number of apertures 44 and these also are provided with plugs 36 (omitted in this view) to permit the operator to stop or plug the apertures 44 which, for the time being, he does not desire to use.

It will be noted that the spring 45 urges the lip 42 toward the inner side face of the side wall of outrigger box 16 and therefore into hooking or latching engagement with the apertures 14 as the outrigger beam 17 is moved outwardly from the box. The latch 34' is provided with an expansion spring 46 which urges the latch 34' into locking engagement with the jack 18 and it will be noted that as the lip 42 engages in aperture 44 continued outward movement of the beam 17 by reason of the hydraulic cylinder 32 will cause the lip 40 to be withdrawn from confining the jack 18 and continued expansion of hydraulic cylinder motor 32 will cause the jack 18 to be disposed in its supporting position. Reverse powered movement of the cylinder 32 will effect movement of the jack to its normal position disposed within the beam 17.

Having thus described our invention, we claim:

1. In a mobile crane or the like, an outrigger support comprising a horizontally extending outrigger box carried by the frame of said crane; a tubular outrigger beam telescopically associated with said outrigger box; power means operably connected to selectively extend and retract said outrigger beam; a supporting jack carried by the beam normally disposed in an inoperative position and operably connected for movement by said power means to a depending position at the outer end of said

outrigger beam; and means normally securing said beam and jack together in said inoperative position and actuatable at a selected one of a number of predetermined relative telescopic positions of said box and beam to a releasing position, whereby said power means successively effects telescopic movement of said beam to said telescopic position and subsequently moves said jack to its operative position.

2. In a mobile crane or the like an outrigger support comprising an outrigger box carried by the frame of said crane and horizontally extending transversely thereof; a reciprocable tubular outrigger beam telescopically associated with said outrigger box; a support jack normally disposed axially in said beam and movable to a supporting position depending at a right angle from the outer end thereof; power means operably connected to said support jack for selectively moving said jack to its supporting operative position and normal inoperative position; and means securing the jack in its normal position to said outrigger beam for effecting telescopic movement of said outrigger beam in said box by said power means and releasable at one of a number of predetermined positions to effect movement of said jack by said power means to its supporting operative position sequentially.

3. In a mobile crane or the like an outrigger support comprising an outrigger box carried by the frame of said crane and horizontally extending transversely thereof; a tubular outrigger beam telescopically associated with said outrigger box and reciprocable therein; a support jack normally disposed axially in said beam and movable to a supporting position depending at a right angle from the outer end of said beam; a latch carried by said beam and movable to an operative position wherein the support jack is releasably secured in its normal position with said beam and to an inoperative position where the support jack is released for movement to its supporting position; power means secured relative to the frame of said machine and adapted to apply pressure axially of said support beam on said support jack and operable to urge said latch to its inoperative position, whereby the jack is moved from its normal position to the supporting position when the latch is in its inoperative position; and means on said outrigger box for actuating said latch when said outrigger beam is disposed in selected telescopic relationship with said outrigger box.

4. In a mobile crane or the like an outrigger support comprising an outrigger box carried by the frame of said crane and horizontally extending transversely thereof; a tubular outrigger beam telescopically associated with said outrigger box for reciprocal movement therein; said beam having at its outer end a support jack movable from a normal inoperative position within said beam to an operative position wherein the jack extends downwardly at a right angle to the beam to support the end thereof; motivating means secured relative to the frame of said machine and operably connected to move said support jack to its depending position; a latch releasably securing said jack in its normal inoperative position rigid with said beam, whereby energizing of said motivating means telescopically extends and retracts said outrigger beam; and means on said outrigger box adapted to actuate said latch at selected outwardly extending telescopic positions of said outrigger beam for effecting movement of said support jack to its supporting position at selected locations.

5. In a mobile crane or the like, an outrigger support comprising a horizontally extending outrigger box carried by the frame of said crane; an outrigger beam telescopically associated with said outrigger box; power means operably connected intermediate a fixed position relative to said frame and said outrigger beam for selectively extending and retracting the beam; a supporting jack carried by the beam and selectively movable alternately to an operative supporting position and an inoperative position by means operably connecting said jack and said powered means; and means normally securing said beam.

and jack together in said inoperative position and actuatable at a selected one of a number of predetermined relative telescopic positions of said box and beam to a releasing position, whereby said power means successively effects telescopic movement of said beam to said telescopic position and subsequently moves said jack to its operative position. 5
